ELECTRIC CONNECTOR.

1,119,864.

Specification of Letters Patent.

Patented Dec. 8, 1914.

Application filed September 11, 1912. Serial No. 719,759.

To all whom it may concern:

Be it known that we, EDWARD J. OVINGTON, a citizen of the United States, and resident of Brookline, county of Norfolk, State 5 of Massachusetts, and JOHN E. HERLIHY, a citizen of the United States, and resident of Cambridge, county of Middlesex, State of Massachusetts, have invented an Improvement 10 in Electric Connectors, of which the following description, in connection with the accompanying drawings, is a specification, like letters on the drawings representing like parts.

Our invention is a connector for an electric 15 circuit of the type comprising a socket member and a coöperating male member, one of them, usually the socket member, being adapted to be attached to the supply circuit and the other, usually the exposed 20 or male member, being adapted removably to fit said socket and to be attached to the article, device or circuit that is to receive current. In connectors of this type it has heretofore been common practice, among 25 various expedients, to slit one of the contacts, as, for instance, the metallic sockets or contact members of the socket-part of the connector so that they may be contracted to a smaller diameter than the pins of the male 30 member, (or so that the pins might be spread, where slotted pins were employed) and thereby pinch or have a spring effect upon the pins when the latter are inserted in circuit closing position, but these are apt 35 to spread and lose their spring effect. It has also been another common practice to have the metal sockets loosely held in their container, but with a wider or narrower spacing between centers than the pins of the 40 male member, so that when the male member is inserted the pins necessarily come into forcible frictional contact with the sockets by being obliged to force the latter somewhat out of alinement in entering, but be- 45 cause of the looseness of these metal sockets their action is somewhat uncertain. Also in both of these common constructions it re- 50 quires some force to push the male member home, and also to remove it, the latter being desirable for insuring a quick break to prevent arcing. Where, however, the connector is attached to a light portable article, or 55 where it would be awkward or difficult to

apply force in removing the separable member, it is a disadvantage to be obliged to exert this force. Accordingly, our invention aims to avoid the necessity of providing slotted sockets or plugs and other well known methods of securing proper contact, and in our preferred construction we provide a spring or springs for deflecting one or both of the metal sockets (or plugs) or moving them sufficiently out of alinement with the pins (or sockets) to insure the desired hard frictional engagement, and as a further feature of the invention we provide means whereby this spring pressure may be momentarily externally released when the device is used in such positions that it is a disadvantage to require a strong pull for disconnecting the parts. Preferably this release is in the form of a push button, connected either directly or indirectly with the spring or extended from or contacting or connecting with the tubular socket or sockets or with the plugs. 70 75

In the drawings, in which we have shown a preferred embodiment of the invention, Figure 1 is a view in front elevation of one form of connector; Fig. 2 is a top plan view 80 thereof; Fig. 3 is a view partly in section showing the internal construction, with one of the inclosing parts removed; Figs. 4, 5, 6 are views similar to Fig. 3 showing modifications; and Fig. 7 is a perspective view of 85 one form of fixed member, showing an instance of the plug or pin member fast on the article.

Referring first for convenience, to the form of our invention shown in Figs. 1-3, 90 the socket member proper 1 for connection to the supply circuit may have a casing or body of any usual or preferred external shape or construction, being shown as consisting of two similar halves or parts 2, 3 95 secured by screw bolts 4, 5, 6, and recessed at 7 to receive the supply circuit wires from whose branches extend opposite recesses 8, for the terminals or contact tubes 9 (which latter may have any desired cross-sectional 100 shape) said recesses 8 terminating in reduced openings 10 for directing the co-operating pin-terminals, or plug-contacts 11 of the male part of the connector. The said male part or member may likewise have a 105 casing or body of any usual or preferred

general shape or type, said pins being herein shown as mounted in a plate 12 which may be considered as a conventional showing of the casing or body of such usual male carrying member. As shown in Fig. 3, a spring 13 is carried in a recess 14 to press against the adjacent metal tubular socket or terminal contact 9 and throw it into divergent relation with the other socket or terminal contact, *i. e.* out of alinement or parallelism with the opposite socket 9. Thus, when the pins 11 enter the openings 10, they meet with the frictional resistance when they enter the tubes 9, which is due to one of these tubes being out of axial alinement with the necessary direction of movement of said pins, and preferably divergent therefrom or oblique thereto and this resistance is dependent upon the spring 10. At their lower ends the two tubes are provided with usual binding screws 15 for securing the leading-in wires of the supply circuit. The resistance of the spring makes the position of the metal tubular contact or terminal socket and the friction certain and definite and it insures uniformity of action and is, moreover, inexpensive and not liable to get out of order. As already stated, we do not intend to be limited to the exact position of the spring, nor to the use of one spring, nor to the use of spring pressure against one of the metal contact tubes 9 alone, although the construction shown is preferable for its simplicity and serviceableness.

In Fig. 4 we have shown a socket member containing a spring 16 which operates against both terminals 17, 18, insulating bushings 19 being carried at the ends of the springs to engage with the adjacent metal parts. In this construction one or both of the tubes are made movable sidewise, both thereof being herein shown as having slight movement.

In Fig. 5 the desired frictional result is obtained by mounting a spring 20 (and insulating end-bushings 21) between opposite plug terminals or pins 22, 23 of the male member. In order to make our showing comprehensive, we illustrate in Fig. 5 one terminal 22 laterally movable and one terminal 23 stationary, and in Fig. 4 both terminals 17, 18 movable, the latter showing also a parallel movement, while Fig. 3 shows a somewhat swinging movement, as also Fig. 6. In the latter (as in Fig. 3) a spring operates on only one terminal, Fig. 6 showing a connector whose socket member contains a single terminal 25 (preferably tubular) automatically movable in a recess 26 by a spring 27 and a compensating pin 28 in a fixed male member 29. Here the socket member fits and is guided to closed position by the cup-shaped part 30 of the plug member 29.

In Fig. 7 we show two fixed pins or pro-

jecting terminals 31, such for instance as might be used on an electric sad iron, or culinary appliance, to coöperate, for instance, with the socket member shown in Fig. 3 or Fig. 4. So, either of these may receive, or combine with, the male member of either Fig. 1 or Fig. 5.

We now come to the second important feature of our invention,—in such cases, as already mentioned, where it is difficult or undesirable to apply force in separating the pins and the tubes, we provide a push button 16 for counteracting the force of the spring, *i. e.* for alining the contact (tube or tubes, or the pin or pins, as the case may be), said push button being shown in Fig. 3 as extending through the casing or body 1 from the spring-held tube 9. It will be obvious that the push button could be arranged otherwise, so as to relieve the spring pressure, and accordingly it will be understood that attaching the same directly to the metal tube 9 is only a preferred construction.

In Figs. 4 and 5 is a loose button 33, 34, and in Fig. 6 is a wedging stop or actuator 35 mounted to slide in a slot 36 and having an inturned end 37 to push the contact 25 over in opposition to the spring 27. Retracting the stop 35 backwardly, or to the left as shown in Fig. 6, permits the spring to act and deflect the socket 25, thereby insuring the contact with the plug 28. Also it will be understood that we are not limited to a push button specifically, inasmuch as the idea broadly of providing an externally operated means of neutralizing, counteracting, overcoming and removing the effect of the spring is our invention, and while we prefer a device which is movable out and in, we do not intend to be restricted thereto, but any movable part, externally operable either directly or indirectly, which will offset the action of the spring and tend to restore the metal tube or socket-part to proper alinement, or at least so that it does not offer strong frictional resistance, is within the spirit and scope of our invention as hereinafter claimed in its broader aspects.

Having described our invention, what we claim as new and desire to secure by Letters Patent is:

1. An electrical connector, comprising separable members adapted to be attached and detached, in combination with means to secure the electrical contacts of said members under yielding tension, said means consisting in one member having an insulated casing, a contact piece movable within said casing to disaline it therewith, a spring arranged to exert pressure on said movable piece to disaline it, the other separable member acting automatically during attachment, to hold said movable contact piece into alinement in opposition to the spring.

tension, and means to remove the effect of said spring before said members are disconnected.

2. In an electrical connector a socket member comprising a body portion, apertured contacts inclosed in said body portion for frictionally receiving sliding contact pins of a removable coöperating male member, means for yieldingly shifting one of said apertured contacts sidewise in said body portion for increasing its frictional resistance to said male member, and externally operable means for counteracting the influence of said yieldingly shifting means on said apertured contacts.

3. In an electrical connector, a socket member containing two contact tubes, a spring for laterally shifting one of said tubes with relation to the other, and a push button extending externally of said socket member for repressing said spring.

4. In an electrical connector, a socket member containing two contact tubes, a spring for laterally shifting one of said tubes with relation to the other, and a push button extending from said shiftable tubes for moving the same in opposition to said spring.

5. An electrical connector, comprising an insulated casing, a contact piece within said

casing having provision to swing out of alinement, a spring adapted to exert pressure on said contact piece to dis-align it, and manually operable means to remove the effect of the spring pressure.

35

6. An electrical connector, comprising an insulated casing, a contact piece within said casing having provision to swing out of alinement, a spring adapted normally to exert pressure on said contact piece to dis-align it, and means having a manually operable portion exteriorly of said casing to counteract the spring pressure sufficiently to re-align the contact piece.

7. An electrical connector, comprising an insulated casing, a contact piece within said casing having provision to swing out of alinement, a spring normally adapted to exert pressure on said contact piece to dis-align it, and means having a manually operable portion exteriorly of said casing to release said spring pressure entirely.

In testimony whereof, we have signed our names to this specification, in the presence of two subscribing witnesses.

EDWARD J. OVINGTON.
JOHN E. HERLIHY.
